A. P. Haskel

UNITED STATES PATENT OFFICE.

JAMES B. HASKELL, OF HAMILTON, OHIO, ASSIGNOR TO THE AMERICAN FROG & SWITCH COMPANY, OF HAMILTON, OHIO, A CORPORATION OF OHIO.

SWITCH STAND.

Application filed August 19, 1921. Serial No. 493,717.

To all whom it may concern:

Be it known that I, JAMES B. HASKELL, a citizen of the United States, residing in Hamilton, in the county of Butler and 5 State of Ohio, have invented certain new and useful Improvements in Switch Stands, of which the following is a specification.

My invention relates to switch stands, and has for its object the provision of a 10 novel stand of this character having an operating handle which extends in the direction of length of the track and is operable in a direction parallel with the general direction of the track, reducing the necessity 15 of changes in directions of movement of the trainman, thereby economizing in time and effort in operating the switch stand.

It is the object of my invention, further, to provide a switch stand of novel structure 20 whereby the movement of the switch-arm lengthwise of the track is converted into movement crosswise of the track for moving the movable switch rail by novel, simple and durable mechanism; and, further, to provide 25 a switch stand comprising a cover-plate which has operative connection with the movable switch rail, and to provide means so arranged in such manner that the operating parts are self-cleaning.

30 The invention will be further readily understood from the following description and claims, and from the drawings, in which latter:

Fig. 1 is a plan view of my improved device, shown in connection with a switch.

Fig. 2 is a plan view of my improved device in separated relation, partly broken away, and showing the plate and targets in one position in full lines, and in assumed 40 position in dotted lines.

Fig. 3 is a vertical cross-section of the same, taken on the line 3—3 of Fig. 2.

Fig. 4 is a side elevation of the same, with the operating arm removed and the target-shaft partly broken away.

Fig. 5 is a plan view of the base and the parts mounted therein.

Fig. 6 is a longitudinal section taken on the line 6—6 of Fig. 2, partly broken away, 50 and.

Fig. 7 is a bottom view of the closing plate.

The track is represented at 11, in which 55 12 and 13 represent the stationary main rails, the main rail 13 merging into the sta-

tionary rail 14 of the siding. Rails 15, 16, comprise the movable switch rails of a split switch, and are connected by tie rods 17, 18, of which 18 is represented as the head-rod. The movable switch rails are slidable laterally on slide plates 19, 20, 21, and 22. The rail structure may be of any usual or desirable form.

My improved switch stand comprises a base 25, formed with a raised portion or 60 pedestal 26. The base has an opening 27, in which a bevel-gear or pinion 28 is arranged to rock. A plate 31 is provided with a segment gear 32. The plate and segment gear are shown integral with each other for 65 forming a strong structure. The plate is exemplified as a cover-plate and is preferably formed turret-like at its top, having rounded edges 33. When the cover-plate is turned for closing of the movable switch rail 70 of the main track, it is preferably substantially coextensive with the upward portion or the pedestal of the base.

The cover-plate is provided with a flange 75 36, shown as an extension of the cover-plate, 80 for constituting the cover-plate an arm which has connection with the movable switch rails. For the purpose of this connection the flange is provided with a hole 37.

A connecting-rod 41 has a fork 42, by 85 means of which it is connected with the head-rod 18 by an articulation 43. The other end of the connecting-rod is provided with a fork 44. A bolt 45 is received through holes in the tines of the fork 44 and 90 the hole 37 in the flange, being suitably held in place, as by means of a nut 46 and a spring washer 47.

The plate 31 is pivoted to the base, shown 95 effected by providing the plate with a trunnion 51, pivoted in a bearing 52 of the base. The plate is provided with an annular shoulder 53 resting on the bearing 52. The trunnion is held in its bearing by means of a cotter-pin 54, a washer 55 being located between the cotter-pin and the bearing.

The gear 28 forms a rockable gear, and is shown fixed by means of a pin 58 to a shaft 59 journaled in bearings 60, 61, of the base. An operating arm 63 is fixed to the shaft, 105 as by means of a set-bolt 64.

The gear 28 is located in the opening 27 of the base. This opening preferably opens upwardly, so as to permit coaction between the gear and the segment-gear. Is also pref- 110

erably opens downwardly, opening into the space 65 between the head-blocks 66, 67, to which the base is secured, as by means of spikes 68, received through notches 69 in 5 the base.

The upper portion of the pedestal is provided with an upper face 71, located at the side of the opening in the base. This upper face and the upper end of a flange 72 are 10 located about the opening, being preferably on a level with each other. The lower edge 73 of the cover-plate coats with this upper face and edge with a wiping effect, to keep the upper face and edge clean and prevent 15 obstruction thereof by dirt, snow, ice or the like. The cover-plate in its movements back and forth will wipe the upper face of the pedestal of the base, the wiping action being principally toward the outside of the 20 pedestal. If, however, any dirt or obstruction should be received under the cover-plate, such dirt or obstruction will be wiped toward the opening 27 in the base, and dropped past the gear into the space between 25 the head-blocks, for maintaining the operating parts of the mechanism clear and free from dirt.

The operating arm 63 is preferably provided with a weight 75 having a handle 76 thereon. A switch-stand latch of suitable form, shown at 77, may be provided, this latch having a movable latch-member 78, arranged to be received over the operating arm when the latter is in position for closing the 30 movable switch rail of the main track. Release of the latch may be readily effected by means of a treadle 79. A suitable key lock may be provided for locking the parts in latched relation, if desired.

40 My improved device is of simple construction and exceptionally strong. The stand proper is close to the ground so as to occupy little space in a vertical direction. It is so constructed that accidental injury thereto is 45 almost precluded, and so arranged that the operating parts are continuously protected from the weather.

The cover-plate is normally received over the opening to protect the gear mechanism, 50 and over the upper face of the pedestal to protect the latter. It preferably covers the pedestal when in normal relation. The segment-gear is arranged in a segment over the opening and over the upper face of the pedestal. When the cover-plate is swung by 55 operation of the operating arm to close the movable switch-rail for the sliding and opening the movable switch-rail for the main track, the operating plate moves in a 60 plane parallel with the plane of the tracks, with the flange 80 thereof registering with the proximate wall 89 of the opening, the opening being at all times covered by the cover-plate.

65 The switch-stand may be provided with

signaling means, shown comprising a signal-shaft 81, provided with targets 82. The shaft may be also provided with a portion 83 to which for instance a signal lantern of ordinary construction may be secured. The 70 shaft is shown as a square shaft to which the targets are secured, as by means of bolts 84, and nuts 85. It is provided with a reduced end 86, received in a socket 87, whose axis is coincident with the pivotal axis of the 75 cover-plate. A set-bolt 88 is arranged to secure the target-shaft in fixed position.

Having thus fully described my invention, what I claim as new, and desire to secure by Letters Patent, is:

80 1. A switch-stand comprising a base having an upward opening, a rockable pinion in said opening, a cover-plate above said opening pivoted to said base, the lower face of said cover-plate comprising a segment-gear 85 which meshes with said pinion, and an operating arm for said rockable pinion, said cover-plate provided with connecting means for the connecting rod of a switch.

90 2. A switch-stand comprising a base provided with an upper face, said base provided with an opening, a rock-shaft journaled in said base, an operating arm for said rock-shaft, a gear on said rock-shaft in said opening, a cover-plate for said opening pivoted to 95 said base and arranged for connection with the movable rail of a switch, said cover-plate movable crosswise of said upper face and complementary thereto to wipe said upper face, and a segment gear on said cover-plate 100 in mesh with said gear.

95 3. A switch-stand comprising a base having an upper face and forming a housing, a turret-like cover for said housing having a lower face coacting with said upper face for 105 wiping movement therebetween, and a pinion journaled in said base under said turret-like cover, said cover pivoted on an upright axis to said base, said cover provided with a segment-gear in mesh with said pinion, 110 and said cover arranged for operative connection with the movable rail of a switch.

115 4. A switch-stand comprising a base forming a housing, a turret-like cover for said housing, a pinion in said base under said 120 turret-like cover, an operating arm outside said base for said pinion, said cover pivoted on an upright axis to said base, said cover provided with a segment-gear in mesh with said pinion, said cover arranged for operative connection with the movable rail of a switch, and an upright signal rod mounted on and movable with said cover.

125 5. In switch stand mechanism, the combination with the rails of a railway track comprising a movable rail of a switch, of a switch stand at the side of said rails, said switch stand comprising a base, a rock-shaft journaled therein, an arm extending therefrom for moving the same, said arm extend- 130

- ing lengthwise of said rails and operable in the same general direction as the direction of extension of said rails, a cover-plate, gearing below said cover-plate to connect 5 said cover-plate with said rock-shaft, said cover-plate provided with a depending shank having journal connection in said base, and operative connection between said cover-plate and said movable rail.
- 10 6. In switch stand mechanism, the combination with the rails of a railway track comprising a movable rail of a switch, of a switch stand at the side of said rails, said switch-stand comprising a base, a rock-shaft 15 journaled therein, an arm extending therefrom for moving the same, said arm extending lengthwise of said rails and operable in the same general direction as the direction of
- extension of said rails, a cover-plate, gearing below said cover-plate to connect said cover-plate with said rock-shaft, said cover-plate provided with a depending shank having journal connection in said base, operative connection between said cover-plate and said movable rail, and an upright target-shaft 20 fixed to said cover-plate with its axis substantially coincident with the axis of said depending shank.
- 25 In testimony whereof, I have hereunto signed my name in the presence of two sub- 30 scribing witnesses.

JAMES B. HASKELL.

In presence of:—

MARGARET WELSH,
ROBERT J. SHANK.
